JOSEPH DI GIORGIO, OF CAMBRIDGE, MASSACHUSETTS.

SANITARY STRINGER ATTACHMENT FOR CONFECTION-MACHINES.

1,306,216.

Specification of Letters Patent. Patented June 10, 1919.

Application filed February 7, 1919. Serial No. 275,655.

To all whom it may concern:

Be it known that I, JOSEPH DI GIORGIO, a subject of the King of Italy, residing at Cambridge, in the county of Middlesex 5 and State of Massachusetts, have invented new and useful Improvements in Sanitary Stringer Attachments for Confection-Machines, of which the following is a specification.

10 This invention is embodied in an attachment for a machine employed for manufacturing coated confections, the confections being usually cores or bodies coated externally with chocolate, or other material, applied in 15 a liquid or semi-liquid form, the machine including pumping or forcing means causing the liquid material to flow through a suitable outlet or outlets. It is customary to use one machine for different operations attending 20 the manufacture of coated confections, one of these operations being a step known as stringing, or applying to the otherwise completed coating of the confection a string of the liquid material forced by the pumping 25 means of the machine through a flexible tube or hose having a string-forming nozzle, which is adapted to be moved in any desired direction by the operator to deposit on the confection a string of the liquid material to 30 ornament the coating of the confection.

The invention has for its object, first, to provide an attachment comprising a main conduit adapted to be detachably connected with an outlet through which the liquid material is forced by a pump forming a part of the machine, an outlet end to which is coupled a flexible tube or hose having a string-forming nozzle, and an overflow conduit communicating with the main conduit between the intake and outlet ends of the latter, and provided with a spring-closed pressure-relieving valve, said overflow conduit and relief valve preventing variations of pressure on liquid or semi-liquid material 45 conducted by the flexible tube, so that a string is delivered at a uniform speed by the string-forming nozzle, this uniformity of speed being desirable because the operator is enabled thereby to more effectively ornament 50 the confections.

The invention also has for its object to provide an attachment characterized as above stated, the main conduit having a plurality of outlet ends to which a corresponding number of flexible tubes are coupled,

each controlled by a separate operator, means being provided for shutting off the flow through either tube and the overflow conduit being provided with a stop cock, the arrangement being such that when all the 60 tubes are in operation, the overflow conduit may be closed, and when the flow through one or more of the tubes is shut off, the overflow conduit may be opened to relieve the pressure on liquid discharged by the remaining tube or tubes.

Of the accompanying drawings forming a part of this specification,—

Figure 1 is a top plan view of an attachment embodying the invention.

Fig. 2 is an edge view of the same.

Fig. 3 is a section on line 3—3 of Fig. 1.

Fig. 4 is a section on line 4—4 of Fig. 1.

The same reference characters indicate the same parts in all of the figures.

I have shown at 12 in Figs. 1 and 2 the outlet end of a discharge pipe leading from a gear pump forming an element of a well known confection machine, the pump being adapted to force a liquid or semi-liquid 80 string-forming material through the discharge outlet 12. It is not necessary to illustrate and describe the confection machine in detail, machines of this character being well known, and my invention residing only in 85 the improved attachment hereinafter described.

My improved attachment is adapted to be connected as a whole with and supported by the outlet end 12, and includes a main conduit having an intake end 13 provided with coupling means such as a screw thread adapted for detachable connection with the discharge outlet 12, said intake end as here shown being externally screw-threaded and 90 adapted to be engaged with an internal thread in the machine outlet 12.

As shown in the drawings, the portion of the main conduit having the intake end 13 is a pipe length 14 connected with a cross-shaped conduit member 15, which in turn is connected by a short pipe length 17 with a T-shaped conduit member 18. The member 18 is in turn connected by a short pipe length 19 with a coupling member 20, to 100 which is detachably secured a complementary coupling member 21 detachably engaged with an inner terminal member 22 secured to a flexible tube or hose 23. While the tube 23 may be made of rubber tubing, I prefer to 105

make it of a well known flexible steel tubing. The free outer end of the hose is provided with a string-forming nozzle 24.

The main conduit, as here shown, includes 5 two branches, each including one of the arms of the cross-shaped member 15, a shut-off cock casing 25, a short tube length 26, an elbow 27, and a short tube length 28 engaged with a coupling member 20, such as that 10 above described, forming a part of a detachable connection between the branch and another flexible tube 23. The rotary plug members 29 in the cock casings 25 may be turned to shut off said branches so that 15 liquid will flow only through the flexible tube 23 connected with the central conduit member 19.

The T-shaped conduit member 18 is connected by a short pipe length 30 with an elbow 31 with which is connected a pipe length 32. The parts or members 30, 31 and 32 constitute portions of an overflow conduit which includes a shut-off cock casing 33 and a terminal pipe length 34, the outlet end of which 25 is normally closed by a spring-pressed pressure-relieving valve 35. Said outlet end is preferably beveled, as shown by Fig. 3, and the valve 35 is preferably a resilient metal strip attached at 36 to the conduit member 34 and yieldingly closed by a spring 37 interposed between the valve 35 and the head of a screw-threaded stud 38 engaged with the member 34.

It will be seen that when the plug members 29 of the branch shut-off cocks are closed, the material forced into the conduit member 14 is under greater pressure than when the branch shut-off cocks are open. When this condition prevails the plug member 29 of the overflow conduit shut-off cock 35 is opened, so that a part of the material is permitted to escape through the overflow conduit, from which it may flow to a tank, or other receptacle, connected with the pump 40 of the machine. Provision is therefore made for preventing an excessively rapid delivery of the material when only one of the tubes 23 is in operation. When each of the tubes 50 23 is in operation the shut-off cock in the overflow conduit may be closed, in case it is found that there is no excess pressure requiring relief.

The invention may be embodied in an attachment such as would be provided by 55 eliminating the branches of the main conduit, the attachment including a single flexible pipe 23 and the described overflow conduit and its relief valve. The branched conduit and the plurality of flexible tubes 60 23 illustrated are obviously desirable, because they enable several operators to work with the same attachment, the overflow conduit and its relief valve being useful whenever the operation of one or more of the 65 branch conduits is discontinued.

While I have described somewhat in detail the multiplicity of parts or members entering into the construction of the attachment as illustrated, I do not limit myself to this construction, and may provide a main 70 conduit either singly or branched, by any suitable assemblage of conduit members or elements.

When the described attachment is in use, the fixed main conduit and the overflow conduit connected therewith are located above a traveling endless carrier belt on which the articles to be ornamented by stringing are deposited, and by which they are moved horizontally. The flexible tubes 23 depend 75 from the fixed members to which they are coupled, and are manipulated by operators stationed adjacent to the carrier, the fixed portions of the attachment being out of the way of the heads of the operators.

Any suitable means may be provided for supporting the conduit so that the member 14 will not be turned in the outlet portion 12, by the weight of either of the branches.

I claim:

1. A stringer attachment for a confection machine, comprising a main conduit adapted at its intake end for connection with a discharge outlet of the machine, an overflow conduit communicating with the main conduit between the intake and outlet ends of the latter, and provided with a yieldingly-closed pressure-relieving valve, and a flexible manually controlled stringing tube coupled to the outlet end of the main conduit, one end of the tube being free and provided with a string-forming nozzle, said overflow conduit and relief valve preventing an excess of pressure on liquid or semi-liquid material conducted by the tube, so that a string 95 is delivered at a uniform speed by the nozzle.

2. A stringer attachment substantially as specified by claim 1, the said overflow conduit being provided with a shut-off cock.

3. A stringer attachment for a confection machine, comprising a branched main conduit having a single intake end provided with coupling means adapted for connection with a discharge outlet of the machine, and a plurality of outlet ends, all communicating with the single intake end, and flexible tubes coupled to the outlet ends of the main conduit and provided with string-forming nozzles.

4. A stringer attachment for a confection machine, comprising a main conduit, having a single intake end provided with coupling means adapted for connection with a discharge outlet of the machine, main conduit branches having shut-off cocks, the branched conduit thus formed having a single intake end and a plurality of outlet ends, all communicating with the single intake end, and independent flexible tubes coupled to the said outlet ends, and provided at their free 120 125 130 ends.

ends with string-forming nozzles, said tubes discharging simultaneously when said shut-off cocks are opened.

5. A stringer attachment for a confection machine, comprising a main conduit, adapted at its intake end for connection with a discharge outlet of the machine, main conduit branches having shut-off cocks, the branched conduit thus formed having a 10 single intake end and a plurality of outlet ends, an overflow conduit communicating with the branched conduit between the intake end and the outlet ends thereof, and provided with a yieldingly closed pressure-

relieving valve and flexible tubes coupled to 15 the said outlet ends and provided with string-forming nozzles, the overflow conduit and each of the main conduit branches being provided with shut-off cocks, so that the overflow conduit may be closed when the 20 main conduit and its branches are open, and opened when the main conduit branches are closed to compensate for increase of pressure due to the closing of said branches.

In testimony whereof I have affixed my 25 signature.

JOSEPH DI GIORGIO.
